METAL POST.

1,144,476.

Specification of Letters Patent. Patented June 29, 1915.

Application filed December 21, 1914. Serial No. 878,385.

To all whom it may concern:

Be it known that I, GEORGE HUTCHINSON, a subject of the King of Great Britain, and a resident of Chicago, in the county of Cook and State of Illinois, have invented new and useful Improvements in Metal Posts, of which the following is a specification.

This invention relates to metal posts of the kind used for fencing, telegraph posts or for other purposes, and is a further development of the post disclosed in my pending application, Serial No. 779,739.

My earlier post above referred to combines great strength at ground level with relative lightness in weight and has a cross-section which facilitates the attachment of cross arms or of fence wires, and is shaped so that it meets the static resistance of the earth symmetrically when pressed against from the front or from the back, as generally happens in a fence.

My present invention provides however a post which while retaining the above advantages stands up firmly against sideway pressures also, and is therefore more suitable for telegraph posts and the like which may be subjected to strains from all directions. To accomplish this object I provide 30 a camber in the back line of the post whereby a better balance is obtained as set forth below; and I provide converging flanges at the free edges of the post instead of parallel ones, thereby reducing the tendency for that side of the post which is pressed against the earth, when the post is under sideway strain, to buckle inward at ground level; and finally, I provide braces in the interspace between the two sides of 40 the post, whereby the said tendency of one side of the post to buckle inward under a sideway strain is still further provided against.

With these and other objects in view I have illustrated the invention and the several elements forming part of the invention in the attached drawing.

Figure 1 is a perspective view of a sheet metal post provided near its upper end with 50 an insulator arm. Fig. 2 is a side view of the post showing the camber more clearly. Fig. 3 is a perspective section on a larger scale through said post on line 3-3 of Fig. 1; and showing the means for reinforcing the post by bracing. Fig. 4 is a similar sec-

tion through a post, showing the flanging and showing means for attaching a fence wire. Fig. 5 is a diagrammatic view illustrating the function of the camber.

The post indicated at 1 in Fig. 1 is made 60 of sheet metal and consists of four wing portions 2, 3, 4 and 5, substantially of triangular shape. These wing portions are placed with respect to each other so that they taper in opposite directions, the wing 65 portions 2 and 4 tapering upwardly and the wing portions 3 and 5 integral with the first named portions tapering downwardly, longitudinal edges of each of the two upper portions and the two lower portions being 70 in abutment while other longitudinal edges of said portions converge toward each other. The post therefore, has a cross section resembling a V with a contiguous apex line or back line 6 and free edges 7, 8, 9 and 10. 75 It should be noted that this is the preferred construction and that the apex line is not necessarily a sharply defined line, nor is the shape of the wings a geometrically perfect triangle. 80

The longitudinal axis of the post indicated at 11 in dotted lines does not lie in a plane defined by any of the two edges of the post, but the apex or back line of the post, as well as the free edges consists of 85 portions which are angularly offset with respect to each other, whereby a camber is formed in the post. The distance between the axial line and apex line is approximately twice as great as that between axial 90 line and base line of the V-shaped cross section.

Fig. 5 illustrates the function of the camber. If the head of the post were in a straight line with the back of the buried 95 portion (position I), a force acting sidewise against the post in direction of the arrow A would act against the earth resistance, represented by the soil pressure against the other side of the buried triangle, in a small portion near the apex only, and naturally the post would easily yield displacing the opposing small area of soil, and in yielding would rotate about its axis which also would be a disadvantage. The 100 same tendencies would still prevail if the axis of the post would go through a point X midway between the apex and the base line of the V (position II), because of the fact that the side 3 of the post presented to the 110

- earth is at a slant to the direction in which the force A is acting, so that one edge 7 would advance, cutting into the soil and the other edge 8 would recede. Hence the 5 axis is located considerably closer to the base line than the apex, (position III), whereby the tendencies mentioned above are overcome. This can be effected by the provision of a camber, as described and shown.
- 10 For further strengthening the structure of the post or batten, the legs of the V forming the wings 2, 3, 4 and 5 are provided at their free ends with flanges 12 and 13 which are offset from the plane of the wings and 15 which preferably converge as shown in Fig. 2. That portion of the post where the cross section is largest and which is approximately near the point where the post projects from the soil may be provided with a 20 reinforcing element 14 in the form of a stay, brace or bridge, rigidly secured in the interspace between the legs of the V-shaped section. Similar stays or braces may be provided on other portions of the post, if 25 the potential strains to which the post may be subjected make this construction necessary. In Fig. 3 one of these braces is shown in form of channels 14, 14', extending transversely through the post and welded to 30 the wings of the same, the channels being connected by diagonal cross braces 14''.
- I claim:
1. A sheet metal post of open sided cross section tapering from the ground line of the 35 post in both directions, the apex line of the post below the ground being at an angle to the apex line of the post above the ground and the free edges of the post below the ground being located in a plane disposed at an angle to the plane in which the free edges of the post above the ground are located.
  2. A sheet metal post of substantially V-shaped cross section tapering from the 45 ground line of the post in both directions, the apex line of the post below the ground being at an angle to the apex line of the post above the ground and the free edges of the post below the ground being located in a plane disposed at an angle to the plane in which the free edges of the post above the ground are located.
  3. A sheet metal post of substantially V-shaped cross section wherein the four free edges of the post converge in couples in opposite directions, two of the converging edges below the ground being located in a plane disposed at an angle to the plane of the two converging free edges above the ground, the back or apex line of the post 60 consisting of two portions which are angularly offset with respect to each other, whereby a camber is formed in the apex line of the post, said camber deviating a distance of approximately two-thirds of the 65 entire side view of the post from the axis of the same.
4. A sheet metal post of substantially V-shaped cross section tapering in opposite directions, the apex or back line of the post 70 being composed of two portions at an angle to each other, the portions of the free edges below the ground being located in a plane at an angle to the plane in which the free edges above the ground are located, in combination with means for securing wire holding devices to the said free edges of the post 75 above the ground.
5. A sheet metal post of substantially V-shaped cross section having a camber on the 80 apex line of the post and a camber at each of the free edges of the post, the apices of the three cambers formed in this manner occurring at ground level.
6. A sheet metal post of substantially V-shaped cross section having a camber in the 85 apex line of the V and a camber in each of the free edges of the post combined with reinforcing elements secured in the opening of the V at the point where the post emerges 90 from the ground.
7. A sheet metal post of open sided cross section tapering from ground level in opposite directions, having a side which is presented at a slant to the opposing earth, and 95 being cambered on back and front edges; said camber being greater along that line, as seen in side view, toward which the slanting side recedes from the point of the viewer.
- In testimony whereof I affix my signature in presence of two witnesses.
- GEORGE HUTCHINSON.
